UNITED STATES PATENT OFFICE.

FITZLAND L. WILSON, OF WEST BAY CITY, MICHIGAN.

HOOP POINTING AND LAPING MACHINE.

SPECIFICATION forming part of Letters Patent No. 296,496, dated April 8, 1884.

Application filed December 12, 1883. (No model.)

To all whom it may concern:

Be it known that I, FITZLAND L. WILSON, of West Bay City, in the county of Bay and State of Michigan, have invented new and useful Improvements in Hoop Pointing and Lapping Machines; and I do hereby declare that the following is a full, clear, and exact description thereof, reference being had to the accompanying drawings, which form a part of this specification.

This invention relates to an improvement in hoop pointing and lapping machines; and the invention consists in the construction and arrangement of the different parts, all as hereinafter described, and specifically pointed out in the claims.

In the drawings which accompany this specification, Figure 1 is a plan of the machine. Fig. 2 is a vertical section thereof on line X X, and looking toward the rear of the machine. Fig. 3 is a vertical section on line Y Y in Fig. 1, looking toward the front of the machine. Fig. 4 is a cross-section of the machine on line Z Z in Fig. 1. Fig. 5 is a detached sectional perspective of the pointing device. Fig. 6 is a diagram perspective, showing the hoop feeding and pointing device detached from the frame. Fig. 7 is a diagram perspective of the lapping devices. Fig. 8 is a detached perspective of one of the cutter-heads for lapping the hoops.

A is a frame suitably constructed to support all the operating parts in their proper relative position to each other. This frame is provided at a suitable height above the floor with a number of cross-girts, a a, (see Figs. 2 and 7,) which form a horizontal bed or table, over which the hoops to be operated upon are carried from front to rear by the racks or carrier-bars B B, which are constructed and operated as follows, (see Fig. 6:)

b are ledges formed upon the carrier-bars B at equal distances apart.

c c' are cross-heads, to which the carrier-bars B are secured; and d are two parallel guide-rod, upon each of which two of the cross-heads c c' are sleeved.

f is a connecting-rod, which connects the two front cross-heads, c; and f' is a similar rod connecting the two rear cross-heads, c'. Thus the carrier-bars B form, with the connecting-

bars f f', a rectangular frame or carriage, which is adapted to slide back and forth upon the guide-rods d.

C C' are two shafts, the former journaled at the front side and the latter at the rear side of the machine.

D D' are cams, all of the same size and shape. The cams D are secured upon the shaft C, and the cams D' upon the shaft C'.

e e' are friction-wheels journaled in suitable boxes, which latter are secured near the ends of the guide-rods d. The friction-wheels e rest on top of the cams D, and the friction-wheels e' rest on top of the cams D'.

E is an eccentric placed upon the shaft C'.

g are two rods connecting the eccentric E with the bar f of the quadrilateral frame by the hinged connections h.

In the operation of the machine the shafts C C' are driven (by connections hereinafter described) at equal speed. This produces, by means of the cams D D', an alternating raising and lowering of the carrier-bars B B, while the action of the eccentric E produces at the same time a to-and-fro motion of the carrier-bars, the combined action giving a so-called "four-motion" feed.

As will be seen from the drawings, the carrier-bars B B are placed in the plane of the bed formed by the cross-girts a of the frame in such manner that they alternately rise above or drop below said bed, while the to-and-fro motion of these carrier-bars is so timed that if hoops are laid upon the bed they are engaged by the ledges b of the carrier-bars, and will be carried from front to rear step by step, each step representing the distance between any two succeeding ledges b upon these carrier-bars.

In the operation of the machine a number of the hoops to be operated upon are placed, one on top of the other, between the upright guides i, which are secured at the front end of the bed of the machine, and by the action of the carrier-bars the hoops will then be withdrawn one by one from the bottom of the pile, and carried step by step over the table of the machine, and it is during such passage that the operations of pointing and lapping are carried out. The guide-rods d, by which the carrier-bars are guided in their action, must

be free to rise and fall, and they are therefore placed loosely in the frame; but they are estopped from end motion by letting them abut against the ends of the frame or other vertical stops placed in proper position. The friction-wheels $e e'$ are held in contact upon the cams D D' by the weight of the parts they support; but to prevent any momentary loss of contact when the machine is running at a comparatively high speed, strong leaf-springs F or equivalent devices are employed to supplement by their tension the action of gravity to hold the friction-wheels $e e'$ in engagement upon the cams D D'.

15 The pointing device (see Figs. 2, 5, and 6) is constructed and arranged as follows:

G is a V-shaped block secured in a stationary position, with its top face in the plane of the table formed by the cross-girts a .

20 G' is a V-shaped knife secured to the end of the lever H, which is pivoted at k to the frame, and passes near its opposite end through a yoke, l, which serves as a guide for the lever H. I is a link connecting the free end of the lever H with one arm of a bell-crank lever, J.

25 K is a pitman pivotally connected to the bell-crank lever J. L is an eccentric secured upon the shaft C and actuating the pitman K.

30 G'' is a pressure-foot of corresponding shape with the block G, and secured the required distance above the same to allow the hoops to pass between.

35 M' M' are pressure-bars, two or more in number. They are placed over some of the cross-girts a , and their front ends are secured the requisite distance above the same, so as to allow the hoops to be entered underneath, while their rear ends are free to rest upon the 40 hoops, and thereby prevent them from buckling.

The pointing device operates as follows: As above described, the hoop-blanks inserted between the uprights $i i$ are carried over the 45 top of the cross-girts a by the carrier-bars B B, whose motion advances the hoops step by step, with an interval of time between each step, when the hoops are at rest. Now, the block G is so placed that one end of a hoop, 50 while at rest, will just cover the block, and the motion of the knife G' is so timed that it descends and raises again during the interval of time the hoops are at rest. The cutting-edges of the V-shaped knife G' just overlap 55 the edges of the block G sufficiently all around to enable the knife to properly cut off all of the hoop-blank projecting over the edges of the block G, thus giving to the hoop a pointed end. The pressure-foot G'' frees the pointed 60 end of the hoop from the knife when the latter is withdrawing. In this manner all the hoops are pointed in succession as they pass over the block G.

To present the ends of the hoops uniformly 65 upon the block G for the action of the pointing-knife, the hoop-blanks placed between the

uprights $i i$ are placed with one end against the stop i' , which is so placed that just enough of the end of each hoop is presented to the action of the knife to form the desired pointing.

70 It will readily be seen that my pointing device cuts after the principle of a pair of scissors, which, as is well known, will require less power to cut than a knife operating at right angles to the plane of cutting, and to produce a still more drawing cut I incline the edges of the knife, as shown in the drawings. Another advantage of my construction is that the knife is freed more readily from the pointed end of the hoop.

75 The devices for cutting and lapping each hoop are constructed and arranged as follows:

$a'' a''$ are transverse girts secured the necessary distance above the cross-girts a , so as not to interfere with the free travel of the hoops over said cross-girts.

80 M is a rock-shaft journaled across the transverse girts a'' .

m is a rocker arm secured to the front end of the rocker-shaft M.

90 $n n'$ are other rocker-arms, secured upon the same shaft, M.

N N' are two carriages adapted to be reciprocated in suitable guides, $o o'$, which are adjustably secured to the transverse girts a'' .

95 The guides $o o'$ are inclined, as shown in the drawings, and their adjustment admits of changing the amount of that inclination within a desirable limit by means of set-screws or otherwise. Each of the carriages N N' has journaled upon it an arbor, $p p'$, upon which cutter-heads, O O', and pulleys $q q'$ are respectively secured. The cutter-head O is provided with two planer-knives of the usual description; but the cutter-head O' has two planer-knives, 100 P, which have indented cutting-edges, as shown in Fig. 8, and the indentations of one knife alternate with the indentations of the other knife. The carriage N' has another pulley, q'' , journaled upon it, and a spring pressure-foot, 105 Q, is secured to it in such manner that it reaches with its free end under the carriage, as shown in Fig. 3. Each of the carriages N N' is connected by links $r r'$ with the rocker-arms n and n' , respectively, and these links are provided with suitable devices for lengthening or shortening them within certain limits. The rocker-arm m upon the end of the shaft M is connected by a link, m' , with one arm of the bell-crank 110 lever J, and this link is also provided with devices for lengthening or shortening it.

115 R is a belt passing under the pulley q' and over the pulley q'' of the carriage N', and also over the pulley q of the carriage N, thereby communicating motion to the rotary cutter-heads O O'. 120

Near the center of the machine is secured a clamping device, which operates in connection with the hoop-lapping devices, and it is constructed as follows:

125 S is a bar pivotally secured at the rear end to one of the cross-girts a , while its forward

end engages upon a cam, T, secured upon the shaft C. It is also provided with two upwardly-projecting studs, s s.

S' is a resistance plate or bar adjustably secured to the frame of the machine above the bar S.

The operation of this clamping device is as follows: The action of the cam T upon the clamping-bar S produces an alternate raising and lowering of said bar, and this motion is so timed that the interval in which said bar is raised corresponds with the interval during which the hoop-blanks, passing over the top of the cross-girts a, are also at rest, and the studs s s, being secured in proper position upon the bar S, and also of proper length, are adapted to firmly clamp two of the hoop-blanks against the plate S'. The object of this clamping is to hold the two hoops which are operated upon by the lapping devices against end-wise displacement.

The operation of the lapping device is as follows: The cutter-heads O and O' are rotated by means of the belt R, and the carriages N and N' are reciprocated by means of the rock-arms n n', which derive their motion, by means of the connections described, from the bell-crank lever J, which in turn is actuated by the eccentric L upon the shaft C. The cutter-heads O O' are secured in such position upon the carriages N N' that the cutter-knives are adapted to operate in the desired manner upon the ends of the hoop-blanks whenever the carriages are pushed outwardly, and said motion is so timed that it corresponds with the interval of time during which the hoop-blanks are stationary upon the table. As the length of the lap will depend upon the degree of inclination of the inclined guides o o' and their height above the table upon which the hoop-blanks travel, the necessary adjustability is given to these guides. The cutter-heads O O' do not act simultaneously upon the same hoop-blank. The cutter-head O acts first in lapping that end of the hoop-blank which has been pointed, and as it is customary to cut but a short lap on that end, the carriage N is more inclined than the carriage N'. As the hoop-blanks generally vary a little in length, provision has to be made to present the ends of the same in proper position to the action of the cutter-head O', as any irregularity in length will appear upon the end presented to this cutter-head, and this is done by the following device, (see Fig. 3):

U is a vibrating arm pivotally secured with its lower end to the frame A.

V is a rod pivotally connected at one end with the vibrating arm U and at the other end with an arm, W, which is secured to the carriage N. It will be seen that the reciprocation of the carriage N vibrates the arm U, which is so placed that its upper end acts like a butting device upon the end of that hoop-blank which is presently to be submitted to the action of the cutter-head O', and which

has already been pointed and lapped upon its other end. The arm U has a sufficient degree of vibration to adjust all the hoop-blanks whose length is within the ordinary range of variation from the standard length to which the machine is adjusted, bringing the butt-end of each in the required position for being lapped properly by the cutter-head O'. The spring pressure-foot Q holds the butt-end of the hoop-blank firmly down upon the bed Q' while it is being lapped.

The function of the clamping-bar S, to prevent the hoop-blanks from being pulled lengthwise by the action of the cutter-heads, has been described heretofore.

The bulk of the hoops are now manufactured from elmwood, and the use of the ordinary planer-knife for lapping such hoops is very liable to tear off cross-grained portions, besides producing a rather hacked-up or torn appearance; but I have succeeded in overcoming this difficulty by the use of planer-knives with indented cutting-edges, as shown, with the indentation of one knife alternating with the indentation upon the other or succeeding knife. The knives I use on the cutter-head O are provided with the usual cutting-edge only, as the lap upon the pointed end of the hoop is so short that the ordinary planer-knife will do.

Now, all that remains to be described is the manner in which motion is communicated to my machine.

u is the main drive-pulley, secured upon the shaft v, which is journaled to one end of the frame; and w is another pulley, secured upon the same shaft.

v' is a shaft journaled in the frame upon the opposite end of the machine, and w' is a pulley sleeved upon this shaft. The belt R passes over the two pulleys w w', and communicates its motion to the cutter-heads O O' by means of the pulleys q q', journaled upon the carriages N N', which latter draw apart whenever the cutter-heads are to operate, thus producing the tightening of the belt R at the proper time.

To the loose pulley w' is secured a taper pulley, w''.

w'' is a taper sleeve feathered upon the shaft v', and adapted to be engaged with or disengaged from the taper pulley w' by its engagement with the rock-shaft x', which can be operated at the front side of the machine by means of the shipping-lever x''.

y y' are bevel-pinions upon the shaft v', engaging with bevel-gears z z' upon the shafts C and C', respectively.

As all the motion of the operating parts of the machine is derived from the shafts C C', the shipping of the lever x'' throws the machine in or out of operation.

What I claim as my invention is—

1. In a hoop pointing and lapping machine, and in combination with the table upon which the hoop-blanks are supported, two or more

carrier-bars extending across the table of the machine, and provided with racks or retaining-ledges to engage with the hoop-blanks, in combination with devices for imparting a four motion feed to said carriers, whereby the hoop-blanks are carried intermittently over the table from front to rear, substantially as and for the purposes described.

2. In combination with the stationary table 10 of the machine, and the pressure-bars M, secured above said table, a carriage operating in the plane of said table, and actuated by mechanical devices which give it a to-and-fro and up-and-down motion, whereby the racks or 15 carrier-bars B B, which are secured to or form the ends of said carriage, form a feeding device by which the hoop-blanks are intermittently carried over the table from front to rear, substantially as and for the purpose described.

3. In a hoop pointing and lapping device, the combination of the feed-carriage with an eccentric, E, which imparts a to-and-fro motion thereto, and with the cams D D' D', upon which the four corners of the carriage 25 are supported, and which impart an up-and-down motion to said carriage, substantially as and for the purpose specified.

4. In a hoop pointing and lapping machine, the combination of the carrier-bars B B, cross-heads e e', attached to the under sides of said bars, guide-bars d, passing through said heads, transverse bars f f', connecting the cross-heads e and e', respectively, eccentric E, for imparting a reciprocating motion to the said 35 carrier-bars B, rods g g, connecting the eccentric to the bar f, friction-rollers e e', attached to the outer ends of the guide-bars d, and cams D D', engaging with the rollers and constructed to give a vertically-reciprocating motion 40 to the said bars B, substantially as and for the purpose specified.

5. In a hoop pointing and lapping machine, the combination of the carrier-bars B B, constructed to have a rising-and-falling and to-and-fro motion, with the guides i i, secured to the front end of the table of the machine, whereby the hoop-blanks formed in a pile between these guides may be withdrawn therefrom by the carrier-bars one by one and carried over the table, substantially as described.

6. In a hoop pointing and lapping machine, a lapping device consisting of two reciprocating carriages supported in guides oppositely inclined above the table over which the 55 hoop-blanks are carried, and each provided with a revolving cutter-head, substantially as and for the purposes described.

7. In a hoop pointing and lapping machine, the combination of the shaft C, eccentric L, 60 mounted on said shaft, rod K, attached to said eccentric, lever J, joined to the rod K, link I, depending from and joining the levers J and H, lever H, and knife G, mounted on said lever H, all combined and operating substantially as described.

8. In a hoop pointing and lapping machine,

a carriage reciprocatingly actuated by suitable devices between inclined guides adjustably secured above the table over which the hoop-blanks are carried, in combination with a revolving cutter-head secured upon said carriage, and the spring pressure-foot Q, substantially as and for the purposes described.

9. A clamping device adapted to prevent the hoop-blanks from being pulled endwise 75 while operated upon by the lapping device, consisting of the bar S, pivotally secured at its rear end to the main frame, and provided with the studs s, in combination with a resistance-plate, S', adjustably secured to the main 80 frame, and means, as T, whereby said clamping device is operated, substantially as described.

10. The clamping device designed to prevent the loops from being pulled endwise by 85 the action of the cutter-knives which perform the lapping, the same consisting of the bar S, pivoted at one end to the frame below the table, and engaging with its free end upon a cam which intermittently lifts the bar, and thereby 90 presses one or more hoop-blanks between it and the stationary pressure bar or plate S', secured above the table, substantially as described.

11. In a machine for pointing and lapping 95 hoops, and in combination with the two carriages, N N', provided with cutter-heads O O', pulleys q and q', journaled upon the same, and the belt R, passing over said pulleys and communicating motion thereto, devices for operating the two carriages simultaneously, so that the belt is tightened when the cutter-heads are in operation, substantially as described.

12. The combination of the carriages N N', bearing revolving cutter-heads O O', with the 105 rock-shaft M, rocker-arms n n', secured to the shaft M, and links r r', joining said arms with the carriages, substantially as set forth.

13. In combination with two lapping devices arranged to operate successively one on 110 each end of a hoop-blank, a butting device constructed to push the ends of the hoops to be lapped, varying in length, to a regulated distance from the cutter-head, substantially as and for the purpose specified.

14. In a machine for pointing and lapping 115 hoops, the butting device herein described, consisting of the vibrating arm U, pivotally attached to the main frame, rod V, attached to said arm, and arm W, attached to the rod V 120 and to the carriage N, substantially as and for the purpose specified.

15. In a machine for pointing and lapping 125 hoops, and in combination with the feeding-carriage thereof, mounted on cams secured to shafts C C', located at the front and rear of the machine, respectively, and deriving its motion from an eccentric on one of the said shafts, and the lapping devices, means for imparting motion to the said shafts and lapping devices, 130 consisting of the bevel-gears z', secured to the outer ends of said shafts, bevel-pinions y', mesh-

ing with said gear, shaft v' , carrying the said pinion on its opposite ends, taper sleeve w' , feathered to the shaft y' , pulley w' , loosely mounted on the shaft v' , and provided with the taper projection w^2 , to engage with the taper sleeve w^3 , belt R , imparting motion to the pulley w' , rock-shaft x' , engaging with the sleeve w^3 , and shipping-lever x^2 , attached to the shaft x' , all constructed and operating substantially as and for the purposes specified.

16. In a machine for pointing andlapping hoops, the combination of the following parts: a table upon which the hoop-blanks are supported, a carriage constructed to have a rising-and-falling and to-and-fro motion, which carries the hoop-blanks intermittently from front to rear, taking them one by one from the bottom of a pile of hoop-blanks placed

between guides in the front end of the machine, a pointing device pointing the hoops 20 by a shearing action, two reciprocating carriages supported in inclined guides above the table, and provided with cutter-heads which lap the hoop-blanks upon their ends lengthwise the grain, a clamping device which prevents the hoop from being pulled laterally by the action of the cutter-heads, and a butting device which adjusts each hoop-blank lengthwise before it is lapped by the second cutter-head, all combined and operating substantially as and for the purpose described.

FITZLAND L. WILSON.
